(57) **CLAIM**

The ornamental design for a shower head, as shown and described.

DESCRIPTION

FIG. 1 is a top-left-front perspective view showing the shower head of our design;

FIG. 2 is a bottom-right-rear perspective view thereof;

FIG. 3 is a front view thereof;

FIG. 4 is a rear view thereof;

FIG. 5 is a right-side view thereof;

FIG. 6 is a left-side view thereof;

FIG. 7 is top view thereof; and,

FIG. 8 is bottom view thereof.

Broken lines and unshaded surfaces adjacent to broken lines illustrate portions of the shower head that form no part of the claimed design.

1 Claim, 7 Drawing Sheets
